RAM-JET MISSILE

Alfred J. Bell and Carl W. Besserer, Silver Spring, and
Everard A. Bonney, West Hyattsville, Md., assignors
to the United States of America as represented by the
Secretary of the Navy

Application April 5, 1949, Serial No. 1,800

Term of patent 14 years

(Cl. D71—1)

Fig. 1 of the drawing is a perspective view of a ram-jet missile as it would appear from a point off to the side and slightly below the missile while the latter is in flight;

Fig. 2 is a front elevation of the ram-jet missile; and

Fig. 3 is a side elevation of the ram-jet missile depicted in Figs. 1 and 2.

We claim:

The ornamental design for a ram-jet missile, substantially as shown.
